Primary Examiner — Anhdao Doan*Assistant Examiner* — Mary Shannon Malley(74) *Attorney, Agent, or Firm* — Quarles & Brady LLP(57) **CLAIM**

The ornamental design for an aliquot tray, as shown and described.

DESCRIPTION

FIG. 1 is a top, front, and left perspective view of an aliquot tray according to our new design;

FIG. 2 is a top plan view thereof;

FIG. 3 is a bottom plan view thereof;

FIG. 4 is a front elevational view thereof, the rear elevational view thereof being a mirror image of the front view shown;

FIG. 5 is a left side elevational view thereof; and,

FIG. 6 is a right side elevational view thereof.

The broken line representations in the figures show unclaimed environment and form no part of the claimed design.
